UNITED STATES PATENT OFFICE.

JESSE M. THOMAS, OF PINE LAWN, MISSOURI, ASSIGNOR OF ONE-THIRD TO WILLIAM D. GRUELLE, OF ST. LOUIS, MISSOURI.

SPARK PLUG.

Application filed November 30, 1923. Serial No. 677,678.

To all whom it may concern:

Be it known that I, JESSE M. THOMAS, a citizen of the United States of America, a resident of Pine Lawn, in the county of St. Louis, State of Missouri, have invented certain new and useful Improvements in Spark Plugs, of which the following is a full, clear, and exact description, reference being had to the accompanying drawing, forming 10 a part of this specification.

This invention relates to improvements in electric ignition devices, commonly called "spark plugs", for internal combustion engines, and it consists in the novel features, 15 structure and combination of parts hereinafter described and particularly pointed out in the claims.

The object of the invention is, generally speaking, to provide a spark plug which may 20 be conveniently manufactured and composed of a limited number of parts, and in operation be highly efficient and reliable, and more specifically the object of the invention is to provide a spark plug comprising a main 25 exterior casing and an interior unit including a core, or body, within said main exterior casing. The main exterior casing is screwed into a wall of an engine cylinder, and the interior unit is so arranged that it 30 may be rotated axially relative to said main exterior casing without moving said main exterior casing, thus rendering it possible to secure the spark plug in place in a wall of an internal combustion engine after which 35 the interior unit may be rotated independently of the main exterior casing so that a predetermined portion of said interior unit may be faced toward a designated part of 40 said internal combustion engine.

The spark plug disclosed in the present application is particularly intended for use with the improved shield for spark plugs disclosed by me in an application for United States Letters Patent filed November 11, 45 1922, and bearing Serial Number 600,265.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications 50 which come within the scope of the claims hereunto appended.

Fig. I is a front elevation of my improved spark plug.

Fig. II is a vertical section of the spark plug shown in Fig. I. 60

Fig. III is a section on the line III—III of Fig. II.

Fig. IV is a plan view of my improved spark plug.

Fig. V is a perspective view of the shield 65 associated with my improved spark plug.

In the drawing, A designates my improved spark plug which comprises a main exterior casing B and an insulating core, or body, C. The main exterior casing B is provided 70 with a threaded lower portion D and a non-circular wrench-receiving portion E whereby said main exterior casing may be screwed into an internally threaded opening in a wall of an internal combustion engine. The 75 main exterior casing B is, as usual, formed of metal, and said main exterior casing is provided with internal screw threads F, as shown in Fig. II. Arranged within the main exterior casing B is a horizontal annular shoulder 1, which is arranged below the internal screw threads F just mentioned.

Located within the main exterior casing B is an interior core-supporting device 2, said supporting device being constructed of 85 metal and being in the form of a shell having an elongated cylindrical upper portion 3 and a lower cylindrical portion 4. An annular horizontal wall 5 connects the annular wall of the upper portion of the 90 shell with the annular wall of the lower portion thereof. When the spark plug is assembled the lower face of the horizontal annular wall 5 of the core-supporting device 2 rests upon the shoulder 1 within the 95 main exterior casing B, there being a gasket 6 interposed between the opposed faces of said shoulder and said wall.

The insulating core or body C is arranged partially within the main exterior casing 100 B, said core or body being extended above the upper end of said main exterior casing, as shown in Figs. I and II. The insulating core or body C is provided with an enlarged portion C', which is arranged within 105 the enlarged upper portion 3 of the core-supporting device 2, as shown in Fig. II. In assembling the spark plug an annular gasket 7 is interposed between the lower face of the enlarged portion C' of the core 110 C and the top face of the horizontal wall 5 of the core-supporting device 2. The upper

end of the core-supporting device 2 is provided with a comparatively thin annular wall 2', which secures the core C to the core-supporting device 2. This annular wall is bent inwardly so that it overlaps the outer portion of the enlarged portion of the core C, as shown in Fig. II. An annular gasket 7' is interposed between the bent-over annular wall 2' and the top face of the enlarged portion of the core C. The reason for the gaskets 6, 7 and 7' is that the core C is made of an insulating material, such as porcelain, which is usually easily broken, and the gaskets form cushions between said breakable body and the hard metallic parts with which it contacts. An electrode G passes through the core C and extends downwardly therefrom, said electrode being provided with a binder nut G' by which a conductor terminal may be held in contact with said electrode.

8 designates a threaded bushing which is provided with external screw threads. In the assembled spark plug the threaded bushing 8 is screwed into the interiorly threaded upper portion of the main exterior casing B, the lower end of said bushing bearing against an annular face 9 of the core-supporting device 2.

34 S designates a shield which is extended upwardly into the main exterior casing B and secured to the lower cylindrical portion 4 of the core-supporting device 2. The shield S comprises a substantially cylindrical member preferably constructed of spring metal, the annular wall of said member being split, as shown most clearly in Fig. V, whereby said member may expand and contract. The shield S is provided with a pair 40 of outwardly extending ears 10 which are in contact with the lower end of the main exterior casing B, when said shield has been extended the proper distance into said main exterior casing, and said shield is provided with a pair of angularly projected members 11 which are located at the lower end of said shield. Located in the wall of the shield S is an air opening 12, said air opening being provided with an air deflector 13. The air opening and air deflector are formed by cutting a U-shaped slit in the wall of the shield and bending the metal within said U-shaped slit inwardly to form the air deflector. Located in the wall of the shield S adjacent to the upper end thereof is a pair of apertures 14 arranged diametrically opposite to each other, and arranged on the lower portion 4 of the core-supporting device 2 is a pair of pins 15, said pins 15 also being located diametrically opposite to each other. To attach the shield S to the spark plug the upper end portion of said shield is introduced into the lower portion of the main exterior casing B. The shield is then moved upwardly until the lower end of the core-

supporting device 2 passes into the upper end of the shield. The edges of the pins 15 are slightly rounded so that when the upper edge of the shield contacts with said pins said shield will be spread so that said upward movement of said shield relative to said pins may continue until the ears 10 contact with the lower end of the main exterior casing B. With the shield in the position described a rotary movement of said shield 55 will bring the apertures 14 to positions where they register with the pins 15, thus permitting said pins to extend into said apertures whereby said shield is firmly fixed to said core-supporting device 2. The angularly arranged projections 11 function as electrodes and when the spark plug is fully assembled with the shield in place, spark gaps are provided between said angularly arranged projections 11 and the electrode G, as shown in Fig. I.

In the use of a spark plug provided with the shield shown and described herein, carbureted air will be drawn through the air opening 12 and will be deflected by the deflector 13 against the firing points of the electrodes to keep said firing points of the electrodes clean. To obtain the best results it is necessary that the open portion of said shield be faced toward the inlet valve of the internal combustion engine with which the spark plug is associated. Heretofore it has been necessary to screw the ordinary spark plug into the opening in the wall of the engine and after said spark plug was firmly seated to place a mark of some sort on that portion of the upper portion of the spark plug which faced the inlet valve of the engine. The spark plug would then be removed from the engine and the shield 100 would be attached to said spark plug so that the open portion of said shield was on the same side of the spark plug as the mark. When the spark plug was again placed in the engine after the procedure just recited 105 the open portion of the shield would be properly positioned relative to the inlet valve of the engine. My improved spark plug is provided with a mark such as that indicated in Fig. I by the reference character H. The apertures 14 in the wall of the shield S and the pins 15 on the portion 4 of the core-supporting device 2 are so arranged that the open portion of said shield will be on the same side of the core as the mark H 110 when said shield is secured to said core-supporting device. To locate my improved spark plug properly within an engine cylinder, the assembled spark plug is screwed into the internally threaded opening in a 115 wall of the engine as would any other spark plug. It may then be found that the mark H and consequently the open portion of the shield S are not facing the inlet valve of the engine. In that event it is only neces- 120 125 130

sary to unscrew the threaded bushing 8 so that the pressure of said bushing is removed from the face 9 of the core-supporting device 2. It will be remembered that the 5 core-supporting device is securely fixed to the core C so that said core may not rotate while said core-supporting device is gripped between the lower end of the bushing 8 and the annular shoulder 1, but when the pressure 10 has been relieved by unscrewing the bushing, the core C, core-supporting device 2 and shield S may be freely rotated as a single unit. The core may therefore be rotated until the mark H faces the inlet 15 valve of the engine, in which position the shield S will be properly positioned with relation to said inlet valve. After the core C has been properly positioned the threaded bushing 8 will be screwed downwardly until 20 the lower end thereof bears firmly against the core-supporting device 2, whereby said core-supporting device will be firmly gripped between the lower end of said bushing and the shoulder 1, thus preventing accidental 25 movement of said core. It will be noted that the lower end of the bushing 8 bears against the metallic core-supporting device 2, consequently there is very little danger that the core C will be cracked when 30 said bushing is screwed downwardly to clamp said core in place.

I claim:

1. A spark plug comprising an exterior member adapted to be secured in a wall of 35 an engine, an interior unit within said exterior member, said interior unit including a core, an electrode supported by said core and a shield provided with a second electrode, said shield being arranged adjacent to the lower end of said first mentioned electrode and being provided with a deflector adapted to deflect carbureted air against the firing points of said electrodes, said interior unit being rotatable axially relative to said 45 exterior member and means whereby said interior unit may be retained in a fixed position relative to said exterior member.

2. A spark plug comprising an exterior member adapted to be secured in a wall of 50 an engine, an interior unit within said exterior member, said interior unit comprising a core, an electrode supported by said core, a core-supporting device and a shield provided with a second electrode, said shield being arranged adjacent to the lower end of the first mentioned electrode and being removably attached to said core-supporting device and said shield being provided with a deflector adapted to deflect carbureted air 55 against the firing points of said electrodes, said interior unit being rotatable axially within said exterior member, and means whereby said interior unit may be retained in a fixed position relative to said exterior member.

3. A spark plug comprising an exterior member adapted to be secured in a wall of an engine, an interior unit within said exterior member, said interior unit comprising a core, an electrode supported by said core, a core-supporting device to which said core is fixed and a shield provided with a second electrode, said shield being arranged adjacent to the lower end of said first mentioned electrode, and means whereby said shield is removably attached to said core-supporting device, said means comprising pins arranged on said core-supporting device which pins are adapted to enter apertures in the wall of said shield, said interior unit being rotatable axially within said exterior member and means whereby said interior unit may be retained in a fixed position relative to said exterior member. 75

4. A spark plug comprising an exterior member adapted to be secured in a wall of an engine, an interior unit within said exterior member, said interior unit comprising a core, an electrode supported by said core, a core-supporting device to which said core is fixed, a shield provided with a second electrode, said shield being arranged adjacent to the lower end of said first mentioned electrode, and means whereby said shield is removably attached to said core-supporting device, said means comprising pins arranged on said core-supporting device which pins are adapted to enter apertures in the wall of said shield, said shield being provided with an aperture through 90 which carbureted air is drawn against the firing points of said electrodes, said interior unit being rotatable axially within said exterior member, and means whereby said interior unit may be retained in a fixed position relative to said exterior member. 95

5. A spark plug comprising an exterior member adapted to be secured in a wall of an engine, an interior unit within said exterior member, said interior unit comprising a core, an electrode supported by said core, a core-supporting device to which said core is fixed, a shield provided with a second electrode, said shield being arranged adjacent to the lower end of said first mentioned electrode, and means whereby said shield is removably attached to said core-supporting device, said means comprising pins arranged on said core-supporting device which pins are adapted to enter apertures in the wall of said shield, said shield being provided with an aperture through 100 which carbureted air is drawn against the firing points of said electrodes, and a deflector on said shield adjacent to said aperture, said interior unit being rotatable axially within said exterior member and means whereby said interior unit may be retained in a fixed position relative to said exterior member. 105

6. A spark plug comprising an exterior member adapted to be secured to a wall of an engine, an interior unit within said exterior member, said interior unit including
5 a core, an electrode supported by said core, a second electrode, and a shield, said shield being arranged adjacent to the lower end of the first mentioned electrode and being provided with a deflector adapted to deflect

carbureted air against the firing points of 10
said electrodes, said interior unit being rotatable axially relative to said exterior member, and means whereby said interior unit may be retained in a fixed position relative to said exterior member. 15

In testimony that I claim the foregoing I hereunto affix my signature.

JESSE M. THOMAS.
